UNITED STATES PATENT OFFICE.

JOHN C. SCHAFER, OF TOLEDO, OHIO.

FEED-REGULATOR.

1,059,005.

Specification of Letters Patent. Patented Apr. 15, 1913.

Application filed December 5, 1911. Serial No. 663,972.

To all whom it may concern:

Be it known that I, JOHN C. SCHAFER, a citizen of the United States, residing at Toledo, Lucas county, Ohio, have invented 5 new and useful Feed-Regulators, of which the following is a specification.

This invention relates to feeders for handling materials in definite quantity.

This invention has utility when embodied 10 in a feeder required to deliver material at a constant rate, being especially adapted for automatic operation.

Referring to the drawings: Figure 1 is a 15 side elevation with parts broken away showing an embodiment of the invention as an adjustable predetermined rate feed regulator; Fig. 2 is a fragmentary plan thereof; Fig. 3 is a plan view of the hopper in position as to the regulator; Fig. 4 is a view on 20 the line IV—IV Fig. 1, looking in the direction of the arrow; and Fig. 5 is a detail view in side elevation of one of the wear shoes.

The hopper 1 is provided with an inclined 25 back 2 and sides 3 to opening 4 broadening toward its forward end as shown in Fig. 3. The back 2 runs down with a little clearance from the belt 5, while along the outer face of the sides 3 are provided pockets 6 in each 30 of which is a wear shoe 7 shown as freely movable by its own weight to rest upon the belt 5 and thus automatically take up wear. In placing the blocks or shoes in the pockets 6, clamps 8 (Fig. 5) are applied to maintain 35 the shoes in position, although in normal belt travel they are drawn toward the wider forward end of the hopper, and serve effectively to retain material within the hopper width or area.

40 The forward side of the hopper 1 is provided with a double walled side or a pair of similar sides 8 (Fig. 1) having registering openings 9 on their lower sides. Between these opposing sides 8 which are placed together 45 in the form of a box are antifriction rollers 10 (Fig. 4) between which is mounted the reciprocal controlling means or gate 11 connected by link 12 to adjusting means 13 on the lever 14 which has fulcrum means 15. Mounted on the lever 14 is the indicator 16 movable across the face of the dial 17 mounted on the bracket 15 to permit ready determination of position of the lever 14. To the opposite extremities of this 55 forked lever 14 are connected links 18 provided with adjusting sleeves 19. These

links 18 are connected to levers 30 mounted on the fulcrum brackets 21 and carrying at their extremities, remote from links 18, the roller 22 which is counter-poised by the 60 weights 23 and which may be further adjusted for additional refinement by the weight 34.

As an embodiment of a way handling material, such way in this disclosure is shown 65 as traveling with the material transported. Sustaining said material handling way or conveyer belt 5 is shown the idler 32. Equidistant from this roller 22 are the belt sustaining idlers 25 over which the belt 5 70 travels from drive roller 26 on shaft 27 to the follower 28 on shaft 29. The belt 5 provides a continuous way between rollers or pulleys 26 and 28. These shafts 27 and 29 are mounted in brackets 30 on the frame 31 75 mounted by links 32 actuated by rod 33 to vary the position of upper frame 31 from lower frame 34. This rod 33 is movable in the bracket 35 connected to frame 31 and is locked in adjusted position by the nut 36 on 80 rod 33 and clamp 37 holding bracket 35 in position as to frame 34. By this device for adjusting the position of the conveyer, the chamber or receptacle 1 may be readily placed into position as to any source of supply 85 such as the bin 38.

Were the pull for driving the belt 5 on the loaded portion thereof, the tautness might introduce objectionable variations in the action of the mechanism, especially as the load 90 varied. To eliminate such possible inaccuracies of the device, the shaft 27 has provided thereon the driving pulley 39 to actuate the belt 5 from roller 26 to roller 28 on the upper reach, thus getting a slack on 95 the upper reach or conveyer section.

In operation the material from the source of supply in bin 38 falling into the hopper 2 is drawn therefrom by belt or material handling way 5 in such quantity as the lift 100 of the gate or chamber discharge control means 11 may permit as set and controlled by the mechanism.

Many classes of material vary in their feed quantity as to atmospheric conditions 105 or other conditions of fineness or moisture. In many classes of work it is desirable to insure the handling of a predetermined quantity of material as to weight. In this instance should the material upon belt or 110 way 5 fall below the weight determined upon as adjusted by the balance weight 24,

the pulley 22 will lift the belt section 5 and cause a further opening of the gate 11 by means of the levers 20 and 14 with connected parts resulting in allowing increased volume 5 of material to be fed upon the belt. As the effect of this increased volume reaches the pulley 22, the mechanism will bring the gate 11 back to its set position for normal operation. Accordingly, there is accurate and 10 positive control of material volume to be handled by this feeder while operated at constant speed rate. For convenience in instances where totals are desired, there may be provided on shaft 27 an arm 40 to engage spider 41 and thus operate the motor 42, which may be graduated to read linear feet of belt travel or with setting for predetermined quantity of material for running foot on the belt, read directly in any desired 15 notation of pounds, cubic yards, etc.

Should there be an exhausting of material from bin 38 or a clogging therein so that quantity of material upon the belt 5 falls to such a minimum as to tilt lever 20 abnormally, contact 43 thereon shorts between the lines 44, 45, to close an electric circuit including the battery 46 and alarm or electric bell 47 to thus signal attendants.

What is claimed and it is desired to secure 30 by Letters Patent is:

1. The combination with a material handling way, of a movable support for a section of said way, adjustable means for controlling the material supply to said way, and connections from said support for controlling said means.

2. The combination with an endless belt, of a movable support for a section of said belt, a gate for controlling the material supply to said belt, and connecting means from said support for controlling said gate.

3. A feed regulator comprising a hopper with a discharge gate, a conveyer receiving the material from said hopper, means to 45 actuate the conveyer, and means supporting a portion of said conveyer and controlled by the quantity of material thereon and having connections with said hopper gate for controlling the same.

4. The combination with a receptacle of a chamber provided with a gate, an endless way leading from said chamber, a movable support for a portion of said way, and connections from said support to vary the opening of said gate.

5. A feed regulator comprising a hopper, a belt forming a portion of the bottom of said hopper for removing material from said hopper, and a gate having actuating means therefor in contact with said belt and controlled by the material thereon for adjusting the hopper discharge. 60

6. The combination with a hopper, of a continuously moving member upon which said hopper may discharge, and a gate provided with automatically reciprocable means to vary the amount of material from said hopper which said member may take, said means provided with connections extending to said member to be actuated by material 65 quantity therein.

7. The combination with a hopper, of an endless belt operable below said hopper to remove material therefrom, and gravity shoes held by the hopper and resting upon 70 the belt to retain material.

8. The combination with a hopper, of a belt below said hopper for removing material therefrom, and automatic wear take up shoes held by the hopper and engaging the 75 belt.

9. The combination with a material handling way of a weighted pivoted lever supporting a section of said way, a hopper with a gate for controlling material supply to 85 said way, and connections from the lever to said gate for controlling the latter.

10. The combination with a conveyer for handling material, of a weighted pivoted lever supporting a section of said conveyer, means to actuate the conveyer, a supply duct 90 provided with a gate for controlling material supply to the conveyer, and connections from the lever to the gate for controlling the latter.

11. The combination with an endless belt for handling material, of an adjustably weighted pivoted lever supporting a section of said belt, means to actuate the belt, a supply duct provided with a gate for controlling material supply to the belt, and adjustable connections from the lever to the 95 gate for controlling the latter.

In testimony whereof I affix my signature in the presence of two witnesses.

JOHN C. SCHAFER.
